UNITED STATES PATENT OFFICE.

WILLIAM STANLEY, JR., OF GREAT BARRINGTON, MASSACHUSETTS, ASSIGNOR
TO GEORGE WESTINGHOUSE, JR., OF PITTSBURG, PENNSYLVANIA.

SYSTEM OF ELECTRICAL DISTRIBUTION AND CONVERSION.

SPECIFICATION forming part of Letters Patent No. 372,943, dated November 8, 1887.

Application filed November 23, 1885. Serial No. 183,724. (No model.)

To all whom it may concern:

Be it known that I, WILLIAM STANLEY, Jr., a citizen of the United States, residing in Great Barrington, in the county of Berkshire and 5 State of Massachusetts, have invented certain new and useful Improvements in Systems of Electrical Distribution and Conversion, of which the following is a specification.

My invention relates to an organization of 10 apparatus for the distribution of electric energy, wherein alternating electric currents derived from any suitable source are transmitted to a point more or less distant and there employed as the means for occasioning the force 15 required to act upon translating devices—such, for instance, as incandescing electric lamps. In the ordinary operation of such a system, or of systems most nearly resembling that employed in carrying out this invention, if the 20 whole or any part of the translating devices are withdrawn or removed from the translating circuit the resistance of such circuit is altered. Such a change of resistance at once gives rise to a variation in the electro-motive 25 force of the current generated. It has been usual to employ induction-coils as converters for transforming the currents of a given electro-motive force into currents of higher electro-motive force, and the latter are employed for 30 operating the translating devices. In an application heretofore filed by me there is described a system of conversion and regulation wherein the changes of resistance in the secondary circuit cause an automatic regulation 35 of the supply in the primary circuit. By the present invention the induction-coil, in the sense in which that term is usually employed, is dispensed with, and the currents employed in the translating-circuit are derived directly 40 from the main-line circuit.

The object of the invention is to provide an automatic means of regulation whereby a constant difference of potential may at all times be maintained in the translating-circuit irrespective of the changes in resistance which 45 occur therein, from which it results that the energy consumed in operating the system may be materially economized.

In general terms, the invention consists of 50 an apparatus whereby a current of variable strength is caused to be developed, the vari-

tions being dependent upon and caused by the variations of resistance in the translating-circuit. To accomplish this there is included in the main circuit of the apparatus an electric generator which is capable of producing approximately constant electric currents in a closed circuit of varying resistance, together with a regulator which comprises one or more pairs of differential helices normally tending 55 to produce equal and opposite magnetisms in a soft-iron core. This is so arranged as to constitute an automatic current-regulating device.

The conductors leading to the translating 60 devices are connected with the respective terminals of one of the opposing coils of the current-regulator, and they thereby form a shunt-circuit around this coil, the resistance of which is dependent upon the lamps or other translating devices included in the circuit. Assuming, in the first instance, that the translating-circuit is open, its resistance will be infinite, and all the current will traverse both regulating-coils. The effect of this current 65 upon the iron core, which is surrounded by the two coils, will be nearly null, and little or no effective magnetism will be developed therein. If, now, the circuit be completed 70 through a translating device having a given 75 resistance, a portion of the current will be shunted from the opposing coil in the main line, and the magnetic equilibrium previously due to the currents traversing the opposing coils will be disturbed, so that a certain 80 amount of magnetism will be developed in the core. The moment that the normal inductive balance between the two opposing coils is thus disturbed the coil preponderating over the other acts to it as a primary to a secondary 85 coil of an inductorium, and vice versa, so that the value of the current shunted is not 90 that simply due to Ohm's law, but, in addition, that which is due to the electro-motive force developed in the weaker coil by the inductive action of the core under the influence 95 of the stronger one. If a second translating device be included in circuit in multiple with the first, a greater amount of current will 100 be shunted around the second coil, and thus the difference between the effects of the two coils will be still further increased, and the

counter electro-motive force due to the magnetization and demagnetization of the core under the influence of the alternating currents will be correspondingly increased. This counter electro-motive force establishes a resistance to the normal main-line currents, which causes a current to be sent through the translating-circuit of sufficiently high electro-motive force to operate the translating devices.

10 If this counter electro-motive force is increased, it is obvious that a higher electro-motive force must be used to force a unit of current through the primary circuit, and, under the conditions hereinbefore stated, the 15 primary generator automatically supplies this increase. The electro-motive force therefore varies inversely as the resistance of the main circuit, but is directly proportionate to the work required to be done in the translating-circuit.

It has been stated that the primary generator is so constructed as to maintain an approximately constant current in its circuit, and hence the potential maintained at the 25 terminals of the translating-circuit will remain approximately constant, and as the resistance between the leaders for this circuit is decreased by the insertion of more lamps the electro-motive force must be increased in order to 30 maintain the current in each multiple-arc branch of the translating-circuits at a given value. The shunting of the opposing coil automatically accomplishes this result.

The accompanying drawing is a diagram 35 illustrating an organization of circuits and apparatus suitable for carrying out the invention.

Referring to the drawing, A represents a magneto or dynamo electric generator or other 40 convenient source of electricity. This generator is designed to transmit alternating or intermittent currents upon a main line, L, and it is constructed in any well-known manner for the purpose of maintaining a constant current—that is to say, a current of a constant 45 number of ampères but variable electro-motive force in the external circuit under conditions of varying resistance. An alternating machine whose field-magnets are supplied by a 50 dynamo, A', and provided with any suitable system of automatic regulation, as shown at A'', will be found well adapted for this purpose.

Included in the main line L is a regulating 55 and converting device, B', consisting of two opposing coils, E' and E'', surrounding a core, F, to which they are applied by any convenient or suitable arrangement of differential winding. A current traversing both of these 60 coils tends to develop nearly equal and opposite polarities in the iron core, and therefore practically no magnetic effects are developed. A conductor, 1, leads from a point, 2, between the two regulating-coils E' and E'', and a similar conductor, 3, leads from a point, 4, at the 65 remaining terminal of the coil E''. Conductors d' d'' d''', &c., are designed to lead from

the conductor 1 to the conductor 3 in multiple arc, and in these the translating devices—such, for instance, as incandescent lamps D' 70 D'' D''', &c.—are designed to be included.

The connections of the conductors d' d'' d''', &c., will be made and interrupted by suitable switches and other devices, b' b'' b''', &c. In this manner the translating-circuit in effect 75 forms a bridge or shunt for the regulator-coil E'. It results from this that the effective strength of the current traversing the coil is determined in the first instance by the difference in the resistance offered to the conductors 80 2 and 3, respectively, and will vary proportionately to the variations in their resistance; but a second factor is immediately introduced, determining the current which will traverse the translating-circuit—namely, the counter 85 electro-motive force, which is immediately developed by reason of the disturbance of the balance between the effects of the coils E' and E''. This counter electro-motive force increases the 90 resistance offered to a current traversing the coil E'', and causes an electro-motive force to be developed sufficient to operate the incandescent lamps or other translating devices included between the conductors 1 and 3. If the resistance of the translating-circuit be increased or decreased by including more or less of the lamps in circuit, then will the amount of current shunted be correspondingly decreased or increased, and a corresponding variation will occur in the resistance due to the 95 opposing coil of the regulator. These variations in resistance act to automatically vary the electro-motive force of the current generated, and it is evident that the limits of this 100 variation will be between a maximum when the whole current is shunted around the coil E'' and a minimum when no current is shunted; so, also, the variation in the current produced will be between the same limits. A minimum amount of energy, therefore, will 105 always be absorbed in generating the current, and the current generated will be at all times dependent upon that consumed by the translating devices. The work expended at this 110 point of local distribution is directly proportionate to the work absorbed, and the same 115 efficiency is secured from a fraction as from a unit of work done.

In all other systems of electrical distribution when the main conductor is divided into 120 branches containing translating devices it has been found necessary to introduce artificial resistance to maintain a constant difference of potential, while varying the joint resistance of such divided circuits. By the 125 present system no artificial resistance is required by reason of the neutralizing effects of the opposed coils upon the same core and the reduction of the magnetic effects due to the 130 changes in such opposition.

It is evident that more than one translating and corresponding regulating system may be applied to the generator-circuit, and in the drawing two additional systems are repre-

sented at B² and B³. The organization of these systems is essentially the same as that already described. When a second system is brought into operation by the introduction of 5 a translating device—as, for instance, a lamp, D', connected with the regulator at B'—then a proportional current is diverted and consumed in operating that lamp, and the resistance of the generator circuit is increased. A 10 current of increased electro-motive force is thereupon generated.

I claim as my invention—

1. The combination, substantially as hereinbefore set forth, of a source of electricity, a 15 soft-iron core, opposing coils surrounding said core and included in the circuit of said source of electricity, conductors leading from the respective terminals of one of said coils, translating devices, and means for including the 20 same in multiple arc between said conductors.

2. The combination, substantially as hereinbefore set forth, with a source of electricity, of one or more sets of opposing magnetizing-coils included in the circuit thereof, a core 25 surrounded by each pair of said coils, conductors leading from the respective terminals of one coil of each of said pair of coils, and incandescent electric lamps or other translating devices included in conductors connecting the conductors leading from the coils, substantially as described. 30

In testimony whereof I have hereunto subscribed my name this 17th day of November, A. D. 1885.
